UNITED STATES PATENT OFFICE.

JOHN E. MATTHEWS, OF FREMONT, NEBRASKA.

BEARING CLAMP AND FILE GUIDE.

Application filed January 13, 1923. Serial No. 612,531.

To all whom it may concern:

Be it known that I, JOHN E. MATTHEWS, a citizen of the United States, residing at Fremont, in the county of Dodge and State 5 of Nebraska, have invented certain new and useful Improvements in Bearing Clamps and File Guides, of which the following is a specification, reference being had to the accompanying drawings.

10 This invention relates to certain improvements in bearing clamps and file guides and it is primarily an object of the invention to provide a mechanism of this general character especially designed and adapted 15 for use in the filing and finishing of bearings for motors, automobiles and the like.

It is also an object of the invention to provide a device of this general character having novel and improved means whereby 20 the bearing to be filed or finished may be effectively held in desired position to be properly engaged with a file and wherein bearings of different sizes or irregular bearings may be held by the same device.

25 Another object of the invention is to provide a novel and improved mechanism of this general character including a gauge for controlling the action of the file upon the bearing in accordance with the requirements of practice.

The invention consists in the details of construction and in the combination and arrangement of the several parts of my improved bearing clamp and file guide whereby 35 certain important advantages are attained and the device rendered simpler, less expensive and otherwise more convenient and advantageous for use, as will be hereininafter more fully set forth.

40 The novel features of my invention will hereinafter be definitely claimed.

In order that my invention may be the better understood, I will now proceed to describe the same with reference to the accompanying drawings, wherein:—

Figure 1 is a view partly in elevation and partly in section illustrating a bearing clamp and file holder constructed in accordance with an embodiment of my invention;

Figure 2 is a fragmentary view in top plan of the structure illustrated in Figure 1;

Figure 3 is an enlarged view partly in section and partly in elevation, the line of

section being taken substantially on the line 3—3 of Figure 1;

Figure 4 is an enlarged fragmentary view in plan of the device as herein disclosed with the file holder and file removed; 60 and

Figure 5 is a fragmentary rear elevational view illustrating in detail a portion of the means for controlling the downward movement of the sleeve or barrel. 65

As disclosed in the accompanying drawings, B denotes a base of desired dimensions and which is adapted to be secured to a suitable support by the screws 1 or otherwise as may be preferred. Extending upwardly from the base B is a pedestal or standard 2 provided at its upper end with a table 3 with one side marginal portion of the table 3 and the upper portion of the pedestal or standard 2 having associated 70 therewith a bracing plate or web 4.

The upper surface or face of the table or platform 3 is provided with an open groove or channel 5 in which is engaged the slide 6. The slide 6 is held within the 80 groove or channel 5 by the plates 7 partially overlying the adjacent portions of the groove or channel 5.

The outer end of the slide 6 is provided with a depending arm 8 through which is threaded a bolt 9, said bolt being in swiveled engagement as at 10 with the table or platform 3. By requisite rotation of the bolt 9, the slide 6 may be moved inwardly or outwardly with respect to the groove or channel 5 as the occasions of practice may require. 85

Extending upwardly from the slide 6 is a post 11 having its upper portion reduced as at 12 and which is adapted to snugly fit 95 within an opening of a bearing A of the general type employed in connection with motors, automobiles and the like.

Spaced from the post 11 is a second post 14 extending upwardly from the table or platform 3 and which also has its upper portion 15 reduced to be snugly received within the second opening of the bearing A. By this means the bearing A is effectively maintained in applied position 100 through the instrumentality of the posts 11 and 14. The adjustment of the plate 6 permits the post 11 to be shifted in accordance with the size of the bearing A or 105 in the event such bearing should be of an 110

irregular type. Extending upwardly from the marginal portion of the table or platform 3 is a pair of spaced arms 16 with which are hingedly connected by the pins 17 or the like to the extremities of an elongated yoke 18. The central portion of the base or intermediate part 19 of the yoke 18 is provided with an outstanding arm 20 to provide means whereby a requisite 10 swinging movement may be given to the yoke 18.

The yoke 18 is of a length to straddle both of the posts 11 and 14 and to extend beyond an applied bearing A. The intermediate portions of the side arms of the yoke 18 are connected by a cross member 21 substantially semi-circular in cross section and which extends within the bearing A, as illustrated in Figures 1 and 3, and 15 when the yoke 18 is swung downwardly relatively to the bearing A it effectively clamps the bearing A in applied position upon the posts 11 and 14. With the yoke 18 in clamping position it is to be noted that 20 the upper marginal portions thereof and also of the cross member 21 terminate below 25 the upper face of the bearing A so that no hindrance or obstruction will be offered to the filing of such face.

30 Extending outwardly from the plate or web 4 is a bracket 22 with which is pivotally engaged a lever 23. Secured to the lever 23 at a point 24 eccentric to the pivotal connection 25 between the lever 23 and the 35 bracket 22 is an extremity of a retractible member 26. The opposite end portion of the member 26 is extended to provide a hook member 27 which engages over the arm 20. With the hook member 27 engaged with the 40 arm 20, the downward swinging movement of the lever 23, as is particularly illustrated in Figure 1 will result in the cross member 21 being effectively held in clamping action upon the bearing A. When it is desired to 45 remove the bearing A it is only necessary to swing the lever 23 upwardly whereupon the hook member 27 can be readily disengaged from the arm 20.

50 With the bearing A in clamped position upon the table or platform 3 the surface of the bearing is adapted to be worked by a file or the like to properly finish or smooth said surface of the bearing or more particularly the ends thereof or to file down said 55 surface of the bearing to the depth or size desired by the operator.

Extending upwardly from the platform or table 3 at the rear portion thereof or at 60 a point substantially directly above the pedestal or standard 2 is an elongated post 28 with which is adapted to be freely engaged an elongated sleeve or barrel 29. Carried by and extending outwardly from the sleeve or barrel 29 is an enlarged head 30, which 65 when the sleeve 29 is in applied position is

adapted to overlie the table or standard 3. The forward longitudinal portion of the head 30 is provided with a notch or recess 31 to receive the upper portion 32 of the post 33 carried by the platform or table 3. The portion 32 of the post 33 is preferably angular in cross section and serves to hold the head 30 in substantially a fixed position. When it is desired to move the head 30 into an inoperative position it is only necessary 75 to raise or elevate the sleeve or barrel 29 forwardly sufficiently a distance to free the head 30 from the portion 32 of the post 33.

Slidably disposed through the head 30 is a pair of parallel rods 34 which have their upper end portions connected by the cross members 35, said members 35 extending below the rods 34. Secured to and underlying the lower faces or edges of the members 34 are the loop members 36 through which are 80 adapted to be directed the opposite end portions of a file F. Threaded from above through one of the cross members 35 is a holding screw 37 which is adapted to have direct contact with an end portion of the file F, as is particularly illustrated in Figure 1, to maintain the file F in applied or working position. The rods 34 together with the head 30 permit the file F to be reciprocated in a fixed path of travel so that the 85 file F will have requisite contact with the bearing A to properly treat the surface thereof either to smooth said surface or to cut down the bearing as may be preferred.

When applying the bearing A it is to be 100 understood that the head 30 together with the parts carried thereby is first swung into an inoperative position and that the yoke 18 is also swung upwardly out of the way.

I also find it of advantage to provide 105 means to positively limit the downward movement of the sleeve or barrel 28 whereby to regulate or control the action of the file F upon the bearing A. As herein disclosed I provide a vertically disposed arm 38 which 110 overlies the rear face of the pedestal or standard 2 and terminates at its upper end in a forwardly directed plate 39 through which the rod 28 is disposed, said plate 39 being capable of freely moving lengthwise of the rod 28. The opposite or lower end portion of the arm 38 is provided with a 115 longitudinally disposed slot 40 through which is directed a clamping screw 41, said screw having threaded engagement with the 120 pedestal or standard 2 as is clearly illustrated in Figure 3.

Extending laterally of the side marginal portion of the arm 38 and herein disclosed as 125 at a point above the slot 40 is a pointer or index 42 which coacts with the graduations 43 suitably produced on the rear face of the pedestal or standard 2 whereby the vertical adjustment of the arm 38 may be readily determined and which is of particular im- 130

portance when the bearing A is being filed down.

The plate 39 carried by the upper end portion of the arm 38 underlies the bearing A

5 so that the downward movement of said sleeve or barrel 29 is positively limited, such limitations also controlling the extent of downward movement of the file F with respect to the bearing A.

10 From the foregoing description it is thought to be obvious that a bearing clamp and file guide constructed in accordance with my invention is particularly well adapted for use by reason of the convenience 15 and facility with which it may be assembled and operated, and it will also be obvious that my invention is susceptible of some change and modification without departing from the principles and spirit thereof and for 20 this reason I do not wish to be understood as limiting myself to the precise arrangement and formation of the several parts herein shown in carrying out my invention in practice except as hereinafter claimed.

25 I claim:—

1. A device of the class described comprising, in combination, a support, means for holding a bearing to the support with its surface exposed, an upstanding post carried by the support, a sleeve slidably and rotatably engaged with the post, means carried by the sleeve for holding a file in position for working engagement with said sleeve, and coacting means carried by the 30 post and said second named means for holding the sleeve against swinging movement.

2. A device of the class described comprising, in combination, a support, means for holding a bearing to the support with its surface exposed, an upstanding post carried by the support, a sleeve slidably and rotatably engaged with the post, means carried by the sleeve for holding a file in position for working engagement with said sleeve, and coacting means carried by the post and 40 said second named means for holding the sleeve against swinging movement when the sleeve is at the limit of its movement toward the bearing.

3. A device of the class described comprising, in combination, a support, upstanding posts carried thereby for engagement with a bearing, and means for holding the bearing in engagement with the posts, said 45 means including a member supported for swinging movement and having a part engaging within the bearing.

4. A device of the class described comprising, in combination, a support, upstanding posts carried thereby for engagement with a bearing, means for holding the bearing in engagement with the posts, said means including a yoke mounted on the support for 50 swinging movement, a cross member carried by the yoke adapted to seat within the bear-

ing, an outstanding arm carried by the yoke, and means engaging said arm for holding the cross member in contact with the bearing.

5. A device of the class described comprising, in combination, a support, upstanding posts carried thereby for engagement with a bearing, means for holding the bearing in engagement with the posts, said means including a yoke mounted on the support for 70 swinging movement, a cross member carried by the yoke adapted to seat within the bearing, an outstanding arm carried by the yoke, and means engaging said arm for holding the cross member in contact with the bearing, said last named means comprising a lever pivotally engaged with the support, and a retractile member engaged with the lever and supporting a hook member to engage the arm of the yoke.

6. A device of the class described comprising a support, means for holding a bearing thereon, an upstanding post carried by the support, a sleeve loosely mounted on the post for swinging movement about the post 80 and sliding movement lengthwise of the post, and file holding means carried by the sleeve.

7. A device of the class described comprising a support, means for holding a bearing thereon, an upstanding post carried by the support, a sleeve loosely mounted on the post, file holding means carried by the sleeve, a plate underlying the sleeve for limiting the downward movement of the 90 sleeve upon the post, and means for adjustably connecting the plate with the support.

8. A device of the class described comprising a support, means for holding a bearing thereon, an upstanding post carried by the support, a sleeve loosely mounted on the post, and file holding means carried by the sleeve, an arm adjustably engaged with the support, said arm having a plate through 100 which the post extends, the plate underlying the sleeve and serving to limit the downward movement of the sleeve.

9. A device of the class described comprising, in combination, a support, means for holding a bearing thereon, an upstanding post carried by the support, a sleeve loosely mounted on the post for movement lengthwise thereof and for swinging movement about the post, a head carried by the sleeve and adapted to overlie the bearing on the support when in one position, and file holding means slidably engaged with said head.

10. A device of the class described comprising, in combination, a support, means for holding a bearing thereon, an upstanding post carried by the support, a sleeve loosely mounted on the post for movement lengthwise thereof and for swinging movement about the post, a head carried by the sleeve and adapted to overlie the bearing on 120

the support when in one position, file holding means slidably engaged with said head, and coacting means carried by the support and the head for holding the head in overlying relation with respect to the bearing when the sleeve is at the limit of its movement toward the bearing.

11. A device of the class described comprising, in combination, a support, means for holding a bearing thereon, an upstanding post carried by the support, a sleeve loosely mounted on the post for movement lengthwise thereof and for swinging movement about the post, a head carried by the sleeve and adapted to overlie the bearing on the support when in one position, file holding means slidably engaged with said head, said head being provided with a recess, and a second post carried by the support and

extending within the recess of the head 20 when the sleeve is at the limit of its movement toward the bearing.

12. A device of the class described comprising a support, means for holding a bearing thereon, an upstanding post carried by 25 the support, a sleeve loosely mounted on the post, and file holding means carried by the sleeve, an arm adjustably engaged with the support, said arm having a plate through which the post extends, the plate underlying 30 the sleeve and serving to limit the downward movement of the sleeve, said arm and support being provided with coacting indicating means.

In testimony whereof I hereunto affix my 35 signature.

JOHN E. MATTHEWS.
